UNITED STATES PATENT OFFICE

SETH R. MILBURY, OF IRVINGTON, NEW JERSEY

CHECKING RING

Application filed March 20, 1928. Serial No. 263,152.

This invention relates to new and useful improvements in checking rings.

The principal object of my invention is to provide a checking ring, preferably made of rubber or other elastic material, that may be used in place of the metal checks now commonly employed in checking clothing or other valuables.

With the foregoing and other objects in view that will appear as the nature of my invention is better understood, the same consists in the novel features of construction illustrated in the accompanying drawings and more particularly pointed out in the appended claims.

In the accompanying drawings, which are for illustrative purposes only and are therefore not drawn to scale:

Figure 1 is a plan view of a rubber checking ring constructed in accordance with my invention.

Figure 2 is an edge view.

Figure 3 is a similar view, looking from the opposite side and Figure 4 is an enlarged detail transverse section, taken on line 4—4 of Figure 1, looking in the direction indicated by the arrows.

Referring to the drawings for a more particular description of my invention, and in which drawings like parts are designated by like reference characters throughout the several views, A designated my checking ring, as a whole, which is preferably made of rubber or other elastic material, although it may be made of metal or composition, if desired.

In practice, the rings are to be worn around the wrist, neck, ankle, leg or arm and will eliminate the use of the metal checks now commonly employed as identification means. The rings may be made in any size or sizes desired to meet the requirements and will bear numbers, as a, which are made into the ring itself and may run from 1 to as high as 1000, if desired. The rings may also bear the name of the establishment or person issuing same, as "Blank baths", indicated at b.

If desired, the ring may be formed at the side with an outwardly and laterally disposed integral loop or perforated extension c, to 50 which may be attached a metal check (not

shown). The rings are to be issued to patrons of the establishment in which they are used, as a receipt for clothing or other valuables when checked in that office and upon the return of the ring to the office, the checker by looking at the number on the ring, may instantly locate the correspondingly numbered drawer or compartment in which the checked property has been placed and will surrender the same.

From the foregoing description taken in connection with the drawings, it is thought that the construction and advantages of my invention will be readily understood without requiring a more extended explanation.

Various changes in the form, proportions and minor details of construction may be resorted to without departing from the principles or sacrificing any of the advantages of this invention as defined in the appended claim.

Having described my invention, what I claim as new and desire to secure by Letters Patent, is:

A checking device adapted to be used for identifying a person with his effects deposited in a particular receptacle, consisting of a ring member adapted to be worn upon a limb of the person and having upon its surface characters identifying the receptacle in which the effects are deposited, said ring member having at its side an integrally joined lug extension adapted to retain an effect identifying check.

In testimony whereof he affixes his signature.

SETH R. MILBURY.
